CLAIM

The ornamental design for a monitor stand as shown and described.

DESCRIPTION

FIG. 1 is a front left perspective view of a monitor stand with mounting arms in a horizontal configuration and mounting brackets in an unfolded configuration according to our design, shown in an environment of use;

FIG. 2 is a front left perspective view thereof;

FIG. 3 is a front right perspective view thereof;

FIG. 4 is a front view thereof;

FIG. 5 is a rear view thereof;

FIG. 6 is a left view thereof;

FIG. 7 is a right view thereof;

FIG. 8 is a top view thereof;

FIG. 9 is a bottom view thereof;

FIG. 10 is a rear right perspective view thereof;

FIG. 11 is a front left perspective view of a monitor stand with mounting arms in a horizontal configuration and mounting brackets in a folded configuration according to our design, shown in an environment of use;

FIG. 12 is a front left perspective view thereof;

FIG. 13 is a front right perspective view thereof;

FIG. 14 is a front view thereof;

FIG. 15 is a rear view thereof;

FIG. 16 is a left view thereof;

FIG. 17 is a right view thereof;

FIG. 18 is a top view thereof;

FIG. 19 is a bottom view thereof;

FIG. 20 is a rear right perspective view thereof;

FIG. 21 is a cross-section view thereof, taken along line 21-21 in FIG. 14;

FIG. 22 is a front left perspective view of a monitor stand with mounting arms in a vertical configuration and mounting brackets in a folded configuration according to our design, shown in an environment of use;

FIG. 23 is a front left perspective view thereof;

FIG. 24 is a front view thereof;

FIG. 25 is a rear view thereof;

FIG. 26 is a left view thereof;

FIG. 27 is a right view thereof;

FIG. 28 is a top view thereof;

FIG. 29 is a bottom view thereof;

FIG. 30 is a rear right perspective view thereof;

FIG. 31 is a cross-section view thereof, taken along line 31-31 in FIG. 24; and,

(Continued)

FIG. 32 is a cross-section view thereof, taken along line 32-32 in FIG. 24.

The evenly-spaced broken lines illustrating the section cuts in FIGS. 14 and 24 form no part of the claimed design. The broken lines illustrating the monitors and cords in FIGS. 1, 11, and 22 illustrate environment while the remaining broken lines in the drawings illustrate portions of the monitor stand that form no part of the claimed design.
